VALVE FOR ROCK DRILLS

Filed Dec. 23, 1929

FIG. 1.

FIG. 2.

INVENTOR.
William A. Smith, Jr.
BY *John A. Ade*
HIS ATTORNEY.

UNITED STATES PATENT OFFICE

WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed December 23, 1929. Serial No. 416,132.

This invention relates to rock drills, but more particularly to a distributing valve for fluid actuated rock drills of the hammer type.

A few of the objects are to obtain a rapid and positive action of the valve and to simplify the construction of valve mechanism of this type.

Other objects will be in part obvious and in part pointed out hereinafter.

10 In the accompanying drawings illustrating the invention and in which similar reference characters refer to similar parts,

Figure 1 is a sectional elevation of a rock drill having the invention applied thereto and showing the valve in position to admit pressure fluid into the cylinder for actuating the hammer piston on its working stroke, and

15 Figure 2 is a similar view showing the valve and the piston in their other limiting positions.

Referring more particularly to the drawings, A designates a cylinder having a piston chamber B to accommodate a reciprocating hammer piston C. The cylinder A has a free 20 exhaust port D which is controlled by the piston C.

A suitable closure is provided for the front end of the piston chamber B by a front cylinder washer E which also serves to centralize 25 a front head F with respect to the cylinder A. The front head F acts as a guide for a working implement G to which the blows of the hammer piston C are transmitted by an anvil block H guided by the front cylinder 30 washer E.

In the rear end of the cylinder A is an enlarged bore J to accommodate a valve chest designated generally by K and comprising in this instance a pair of plates L and O. The 40 plate L is arranged in the rear end of the piston chamber B for which it forms a closure, and the plate O is interposed between the plate L and a back head P which may be clamped to the cylinder A in any well known 45 manner.

Arranged within the back head P is a throttle valve Q having a chamber R into which pressure fluid may be constantly introduced from a suitable source of supply. In the wall of the throttle valve is a port S 50 which registers with a passage T in the back head for admitting pressure fluid into the rear end of a valve chamber U in the plates L and O.

The portion of the valve chamber U formed in the plate L is an enlarged portion W, and the rear portion X of the valve chamber U is of smaller diameter than the portion W and is formed in the plate O. Leading from the front end of the valve chamber U to the rear end of the piston chamber B are inlet passages Y which are located in the front end of the plate L. From the rear end of the enlarged portion W of the valve chamber leads a front inlet passage Z which is formed in the plates O and L and in the wall of the cylinder A. 55 60 65

The inlet passages Y and Z are controlled by a distributing valve b in the valve chamber U. The valve b comprises a body portion c having a bore d therein which is in constant communication with the passage T and through which pressure fluid flows to the rear inlet passages Y. 70

At the front end of the valve b is a head e 75 which cooperates slidably with the enlarged portion W of the valve chamber to guide the front end of the valve.

Intermediate the ends of the valve b is a flange f which is of somewhat smaller diameter than the enlarged portion W of the valve chamber wherein it lies, and the pressure fluid supplied to the front inlet passage Z for impelling the piston C rearwardly flows over the periphery of the flange f to the inlet passage Z. The pressure fluid supply to the front inlet passage z is conveyed from the bore d into the enlarged portion W of the valve chamber U and at a point intermediate 80 85 90 95

the head *e* and the flange *f* by ports *g* in the body portion *c* of the valve.

The rear end of the valve is in the form of a stem *h* which cooperates slidably with the portion *X* of the valve chamber and the end of the stem *h* constitutes a pressure surface *j* against which pressure fluid constantly acts tending to throw the valve forwardly. On the rear end of the head *e* is a second pressure surface *k* which is also constantly exposed to pressure fluid for throwing the valve in a forwardly direction.

At the front end of the valve *b* is an opposing pressure surface *o* which is also constantly exposed to pressure fluid tending to throw the valve rearwardly. The pressure surface *o* is of considerably smaller area than the combined areas of the pressure surfaces *j* and *k* so that in the absence of other forces tending to actuate the valve, the pressures acting against the pressure surfaces *j* and *k* will predominate over that acting against the pressure surface *o*.

Additional means are provided to assist the pressure fluid acting against the constant pressure surfaces for throwing the valve from one position to the other. To this end the rear end of the flange *f* is provided with an actuating surface *p* against which compression from the front end of the piston chamber *B* intermittently acts to assist the pressure fluid acting against the pressure surfaces *j* and *k* to throw the valve *b* forwardly. Similarly, on the front end of the head *e* is an actuating surface *q* which overlies the inlet passages *Y* and against which compression from the rear end of the piston chamber *B* acts to assist the constant pressure acting against the pressure surface *o* to throw the valve *b* rearwardly.

From the foregoing description it is thought that the operation of the device will be apparent to those skilled in the art. This operation may however be briefly summarized and is as follows: With the valve in the position to admit pressure fluid to the rear end of the piston chamber *B* as indicated in Figure 1, pressure fluid will flow through the bore *o* into the front end of the valve chamber *U*, thence through the inlet passages *Y* into the rear end of the piston chamber to drive the piston *C* against the anvil block *H*.

During the admission of pressure fluid into the rear end of the piston chamber *B*, pressure fluid will act against the entire front area of the head *e* of the valve, and the valve will then remain immovable in the rear end of the valve chamber by reason of the fact that the effective area of the pressure surface *k* will then only be equal to the difference between the total area of said pressure surface and the area of the flange *f*.

As the piston moves forwardly and after it has covered the exhaust port *D* the air in

the front end of the piston chamber *B* will be compressed. Such compression will flow through the front inlet passage *Z* and will act against the actuating surface *p* to throw the valve forwardly at the instant the rear end of the piston *C* uncovers the exhaust port *D*. The forwardly acting pressures will then predominate over the opposing pressures since when the piston uncovers the exhaust port *D*, there will be an abrupt drop in pressure beneath the head *e*.

In the new position of the valve, the pressure fluid will flow from the bore *d* through the port *g* into the enlarged portion *w* of the valve chamber, thence over the periphery of the flange *f* and through the inlet passage *Z* to the front end of the piston chamber *B* to drive the piston *C* rearwardly.

The valve *b* will remain seated until sufficient compression is created in the rear end of the cylinder by the piston so that the combined forces of the compression acting against the actuating surface *g* and the pressure acting against the pressure surface *o*, as well as the suction on the flange *f* created by the pressure fluid, will throw the valve again to its initial position, thus completing the cycle of operations.

I claim:

1. In a fluid actuated rock drill, the combination of a cylinder and a piston therein, a valve chest having a valve chamber, inlet passages leading from the valve chamber to the cylinder, a distributing valve in the valve chamber having a bore through which pressure fluid flows to one inlet passage, said valve having a flange over which pressure fluid flows to the other inlet passage and a head slidable in the valve chamber to guide the valve, a port in the valve to convey pressure fluid from the bore into the valve chamber between the flanges, opposed pressure surfaces on the valve constantly exposed to pressure fluid tending to throw the valve, and opposed actuating surfaces intermittently exposed to compression to assist the pressure fluid acting against the pressure surfaces in throwing the valve upon a drop in pressure beneath one or the other of the actuating surfaces.

2. In a fluid actuated rock drill, the combination of a cylinder and a piston therein, a valve chest having a valve chamber, front and rear inlet passages leading from the valve chamber to the cylinder, a distributing valve in the valve chamber having a bore through which pressure fluid flows to the rear inlet passage, a port in the valve to convey pressure fluid into the valve chamber from the bore, a flange on the valve over which pressure fluid flows to the rear inlet passage, a head on the valve cooperating slidably with the valve chamber to guide the valve, pressure surfaces on one end of the valve and on the head constantly exposed to

pressure fluid to throw the valve for opening the front inlet passage, an opposed pressure surface on the head constantly exposed to pressure fluid tending to throw the valve for opening the rear inlet passage, and opposed actuating surfaces on the head and the flange intermittently exposed to compression to assist the pressure acting against the pressure surface in throwing the valve upon a drop in pressure beneath one or the other of the actuating surfaces.

In testimony whereof I have signed this specification.
